UNITED STATES PATENT OFFICE

GERTRUDE BERTHA, OF PHILADELPHIA, PENNSYLVANIA

DUPLEX PILLOW SLIP

Application filed November 4, 1929. Serial No. 404,828.

This invention relates to bed equipment, and has more particular reference to an improved pillow slip or case, as this article is generally referred to in the trade.

5 It is generally the present practice to construct pillows of a feather filling contained within a tick envelope. When used on the bed however, it is a common practice to cover the tick with a pillow case or slip for cleanliness and sanitation, as well as for purposes of æsthetic appeal.

It is a matter of common knowledge that the tick becomes readily soiled, and since it is not susceptible of convenient washing or 15 cleansing, in time it becomes soiled to an undesirable degree and in public places, rather unsanitary.

Even though the pillow case is removed and washed repeatedly, the tick gradually becomes soiled and objectionable.

20 To avoid this to a certain degree, it is now a known practice to provide a sewed on tick cover, generally of a cheap textile nature. However, this cover too, becomes soiled and 25 to wash it means a job in that it must be ripped off and then sewed back on later.

To avoid this, I have evolved and produced a duplex pillow slip structure which embodies inner and outer cases permanently stitched 30 together to provide a complete unit which may be readily placed in position or removed and washed and ironed with facility, the inner case being somewhat smaller than the outer one and such as to cover the otherwise 35 exposed ends of the pillow tick, whereby to maintain a clean and sanitary appealing covering for the pillow.

In the drawings:

Figure 1 represents a perspective view of 40 a pillow within a duplex slip of the type constituting the subject matter of this invention, a portion being broken away to disclose the inner case.

Figure 2 is a view similar to Figure 1 showing 45 the outer case rolled or peeled back to disclose the end construction of the inner case.

Figure 3 is a perspective view with a portion 50 of the outer case broken away and with the flap on the inner case extended to permit it to be tucked in.

Figure 4 is a longitudinal section through the complete structure.

In the drawings and in Figure 3, for example, the reference character 5 designates an ordinary pillow. As seen in Figure 4 this 55 comprises an appropriate filling 6 and a tick envelope or covering 7. The duplex slip comprises an outer open-ended case 8 and the companion inner case 9. The closed ends of these inner and outer cases are turned in and 60 simultaneously stitched together as at 10 in Figure 4 to permanently fasten the two cases together and to provide a single duplex unit.

The inner case is somewhat smaller than the outer one and is intended to snugly 65 conceal the pillow. The open end has an ornamental stitch as at 11 in Figure 3 and an extension 12 which functions as a flap. The flap has the corner portions turned in as at 13 and stitched down to the body portion as 70 at 14 for the sake of rigidity and ornamentation. This flap is tucked into the open end as seen in Figure 4.

On the top of the flap I provide buttons 75 15 which cooperate with the buttonholes 16 in securing the pillow within this inner case. These buttons and buttonholes however, are not absolutely essential. In fact, snap fasteners (not shown) might be substituted or no fasteners employed whatsoever.

When the flap is tucked in, the adjacent 80 open end of the outer case 8 projects beyond as shown for example in Figure 1, and this projecting end may be worked or patterned in any suitable manner for sake of ornamentation.

With this arrangement it will be seen that if the outer case works back while it is in use to expose the inner case, the inner case 85 will prevent soiling of the tick on the pillow, but at the same time the entire slip may be readily removed from the pillow for laundering.

From the foregoing description and drawings, it will be seen that I have evolved and 90 produced a simple and economical double pillow slip embodying inner and outer permanently stitched casings of appropriate configuration and design, such as will promote cleanliness and sanitation, and provide a 100

highly useful article for the purposes specified.

Minor changes in shape, size, materials and rearrangement of features may be resorted to in actual practice so long as they do not depart from the scope of the following claims.

I claim:

- 10 1. In a duplex slip of the class described, an inner pillow-containing casing of textile material open at one end to facilitate insertion and removal of a pillow, said inner casing being provided at said open end with an extended flap adapted to be tucked in for covering the adjacent end of the pillow, together with an outer casing for said inner casing permanently stitched to one end of the inner casing and having its opposite end open and projecting beyond the corresponding open end of said inner casing.
- 20 2. In a duplex slip of the class described, an inner pillow containing casing of textile material open at one end to facilitate insertion and removal of a pillow, said inner casing being provided at said open end with an extended flap adapted to be tucked in for covering the adjacent end of the pillow, together with an outer casing for said inner casing permanently stitched to one end of the inner casing and having its opposite end open and projecting beyond the corresponding open end of said inner casing, said flap being substantially triangular in general configuration, with its apex portion truncated, and separable fasteners serving to detachably connect said flap with the body portion of the inner casing.

In testimony whereof I affix my signature.
GERTRUDE BERTHA.
